SQUEEZE BOTTLE OR THE LIKE

Henry J. Orr, 2834 Vincent St., Cuyahoga Falls, Ohio 44221

Filed Dec. 18, 1968, Ser. No. 15,043

Term of patent 14 years

Int. Cl. D9—01

U.S. Cl. D9—2

Fig. 1

Fig. 3

FIG. 1 is a front elevational view of a squeeze bottle or the like, showing my new design;

FIG. 2 is a side elevational view looking from the right of FIG. 1; and

FIG. 3 is a bottom plan view thereof.

I claim:

The ornamental design for a squeeze bottle or the like, as shown.
